UNITED STATES PATENT OFFICE.

HANNIBAL FELT, OF HAMILTON, OHIO, ASSIGNOR OF ONE-HALF TO HENRY P. DEUSCHER, OF SAME PLACE.

WAGON-BRAKE.

SPECIFICATION forming part of Letters Patent No. 278,924, dated June 5, 1883.

Application filed January 27, 1883. (No model.)

To all whom it may concern:

Be it known that I, HANNIBAL FELT, of Hamilton, Butler county, Ohio, have invented a new and useful Improvement in Wagon-5 Brakes, of which the following is a specification.

My invention relates to an improved construction of those wagon-brakes which operate automatically to check the vehicle on a descending grade, or whenever the team is suddenly halted. For this purpose I employ, preferably, a forked lever, which embraces and is pivoted to the wagon-tongue near its front end, and whose upper portion occupies a staple on the neck-yoke. The forked extremities of this 15 lever are connected by rod with a crank at the mid-length of a cross-shaft that is journaled a little in front of and above the rear axle. Cranks on the ends of this shaft engage in slots in the rear extremity of a swinging frame 20 which is suspended from a transom upon the hounds or reaches within the circuit of the wheel-tire. The front portion of this frame constitutes the brake-bar which carries the shoes or rubbers.

25 The construction of the device is such as to be effective in sudden stopping of the team and in going downhill, and to be inert or brake-free both in forward travel and in the act of backing.

30 In the accompanying drawings, Figures 1 and 2 are side elevations of a wagon (which may be of any customary or suitable construction) provided with my improved brake device, Fig. 1 representing the vehicle in its 35 normal condition, and Fig. 2 with the brake in contact with the wheels. Figs. 3 and 4 represent, respectively, the brake mechanism proper, and the forked lever and neck-yoke as they appear when the brake is in action.

40 A may represent the rear wheels, and B the front wheels, of any wagon.

C may represent customary reaches or hounds, whereby the rear axle, D, is coupled to the bolster E upon the front axle, F, to which 45 the wagon-tongue G is secured in the represented or any customary manner.

H may represent the usual jointed and adjustable brake-rod.

I is a transom, which is fastened athwart the 50 reaches about half the radius of the wheel in front of the rear axle.

Flexibly attached to the ends of transom I, and depending therefrom, are links J, whose lower ends are pivoted to a swinging frame, K, the front portion of which constitutes the 55 brake-bar L, which bears at its extremities the shoes or rubbers M.

The arrangement of the parts is such that the instant it is left at liberty the brake mechanism, by virtue of its simple gravity, recovers 60 the normal position shown in Fig. 1, in which the suspending links J hang perpendicular, and the brake-bar end of the frame K droops forward with its rubbers M out of contact with the wheels. The rear ends of the two 65 sides of the suspended frame K have curved slots k, which are occupied by cranks n at the extremities of a shaft, N, which is journaled athwart the reaches a little in front of and above the rear axle, and which has at mid-70 length a crank, n', that points in the opposite direction to the cranks n, and that connects by customary brake-rod, H, with the forked lower extremities of a lever, P, which is pivoted to the tongue, near the front end thereof, 75 and whose upper portion engages in a staple, Q, on the rear edge of the neck-yoke R, from whose lower side depends a ring or loop, S, which slides freely along the tongue. The staple Q is made wide in the longitudinal direction of the neck-yoke to permit of the play 80 incident to turning to the right or left without interruption of the lever action upon the brake.

The operation of the device is as follows: 85 When the team is dragging the wagon after it, as occurs on all level or ascending roads and on slight declivities, the forward draft of the neck-yoke moves the lever into the position shown in Fig. 1, so as to slacken the brake-rod 90 H, and to permit the parts to sink to and to retain their normal position, with the suspenders J hanging perpendicularly and the rubbers out of contact with the wheels, as shown in Fig. 1. If, now, the wagon crowd upon 95 the team, either by the sudden halting of the latter or by reason of the vehicle descending a steep declivity, the neck-yoke instantly shifts the lever P to the position shown in Figs. 2 and 3, and, drawing forward the rod H, causes 100 the cranks n to traverse the slot k, and finally to bring all the parts to the positions shown

in Figs. 2, 3, and 4, in which the very effort of the rear wheels to rotate operates to increase the brake-pressure, because it tends to shorten the distance between the wheel center 5 and the point of impact of the rubber. In the operation of backing, on the contrary, although the parts are brought to the positions shown in Figs. 2, 3, and 4, the wheel's rotation is not opposed, because it is in the direction (see dotted arrow in Fig. 2) that operates to lift, rather than to depress the rubbers, and thus by increasing their distance from the wheel-centers to relieve their pressure. The brake-stress, being thrown upon points of support at portions of 15 the hounds or reaches in close proximity to the rear axle, is firmly sustained.

I claim as new and of my invention—

The combination, with the means, substantially as set forth, for transmitting motion from the neck-yoke, of the swinging frame K, flexibly suspended from a point in rear of and above the rubbers, said frame bearing the rubbers at its front portion, and having slots k at its rear portion, as set forth.

In testimony of which invention I hereunto 25 set my hand.

HANNIBAL FELT.
